MOLDED BACK PART

Lester S. Macdonald, Beverly, Mass., assignor to
 United Shoe Machinery Corporation, Flemington, N. J., a corporation of New Jersey

Application December 13, 1940, Serial No. 370,037

8 Claims. (Cl. 36—45)

This invention relates to shoe uppers and more particularly to molded back parts or quarter assemblies which are preformed to substantially the shape of the heel end of the last.

In the manufacture of certain types of shoes, such as women's two-part sandals, the back parts or quarter assemblies consisting of upper, counter stiffener and lining pieces adhesively secured together are often premolded on a form which is shaped substantially like the heel end of a last. While the back part is on the form, an attaching flange is usually formed by which the back part is subsequently secured to an insole carried on the bottom of a last. While the form on which the back part is premolded may be shaped substantially like the heel end of a last, it has been found impractical to premold the back part in all cases to the exact final shape it is to assume in the shoe owing to the variety of shapes and styles of lasts. Accordingly, while the premolded back part may have approximately the desired shape, it has been found that some, and in many cases considerable, shaping of the back part is required after the premolding operation to cause the back part to conform to the heel end of the last.

The formation of an attaching flange on the premolded back part has the advantage that the flange predetermines the position of the back part on a last but the flange stiffens the back part so that it resists any change in the shape thereof and difficulty is frequently experienced in making the back part conform exactly to the last. In order to overcome this difficulty it has been suggested (for example in application Serial No. 256,055, filed February 13, 1939, in the name of A. A. Lawson) that the back part be premolded without forming an attaching flange thereon. While such an unflanged unit assembly may be more readily conformed to the heel end of a last, lacking a flange, no means is provided for accurately gaging its position relative to the last.

It is an object of this invention to provide a premolded back part or quarter assembly having a narrow inwardly extending ridge or shoulder above the lower edge thereof which defines the proper lasting margin, the ridge being arranged for engagement by the heel portion of the last, thus overcoming any difficulty in positioning the back part in the correct relationship to the last. This ridge or shoulder, being quite narrow does not offer any substantial resistance to the conforming of the back part to the last on which it is assembled.

The ridge or shoulder defining the proper lasting margin is formed by creasing the materials of the back part thereby rendering the materials relatively inert along the line of crease so that the subsequent formation of an attaching flange after the back part has been assembled on the last requires less force and danger of the upper material being marred or otherwise damaged during the flanging operation is greatly minimized. The lower marginal portion of the back part which extends downwardly from the shoulder may be provided with corrugations to facilitate formation of uniform pleats in a flange to be formed during lasting in a heel seat lasting machine or otherwise.

The shoulder which the last engages may slope downwardly from the edge of the last and the lower marginal portion of the back part below the shoulder may extend substantially normal to the bottom of the last so that the back part may be readily conformed to the last and so that two creases are formed between the upper portion of the back part and the lasting margin. This arrangement provides a gage for positioning the back part on the last and further facilitates the formation of the attaching flange. The reason for this is that instead of making one 90° bend in the material to form the flange, two bends at different points, each substantially less than 90° are made, thus further reducing the danger of damage to the upper material during the flanging operation.

These and other features of the invention will now be described in detail in connection with the drawing, wherein

Fig. 1 is a perspective view partly in section of one form of back part or quarter assembly embodying the present invention;

Fig. 2 is a perspective view of a modified form of back part;

Fig. 3 is a vertical section of a still further modification showing the back part assembled on a last having an attached insole; and

Fig. 4 is a vertical section of the back part of Fig. 1 assembled on a last.

In Fig. 1, a back part 10 is illustrated, the back part comprising an upper 12, a lining 14 and a counter stiffener 16 interposed between the upper and lining. Stitching 18 is provided to secure the upper and the lining together along their upper edges and the upper, lining and counter stiffener may be secured together by any suitable counter paste or adhesive. The back part may be premolded to substantially the shape of the heel portion of a last in any suitable man-

ner, as by a machine of the type illustrated in the Lawson application referred to above. The lower marginal portion 20 of the back part is not turned to form an attaching flange during the premolding operation but forms rather a continuation of the sides of the back part, as in the Lawson application, this portion being substantially normal to the bottom of the last after the back part has been assembled therein as shown in Fig. 4, so that the back part may be readily conformed to the last.

In order that the correct position of the back part on the last may be readily obtained, thereby determining the proper lasting margin, without preforming an attaching flange and thus rendering the back part resistant to changes in shape, a circumferential inwardly extending ridge or shoulder 22 is formed, this shoulder being arranged to be engaged by the edge of the heel portion of the last. This shoulder in the form shown in Fig. 1 provides a shallow surface lying in a plane which is substantially normal to the lower margin 20 (Fig. 4) and extends substantially parallel with the bottom edge. The shoulder is quite narrow compared to the width of the lasting margin and the stiffening effect of this shoulder is negligible compared to that which a preformed attaching flange would impart to the back part. Accordingly, this shoulder offers no appreciable resistance to the conforming of the back part to the heel end of a last but greatly facilitates the proper positioning of the back part on the last.

The shoulder crease 22 may be formed in any suitable manner during the premolding operation as by the addition of the necessary members to the molds of the machine shown in the said Lawson application. The pressure required for this operation renders the materials at the crease sufficiently inert so that resistance to the subsequent formation of an attaching flange after the back part is assembled on a last is substantially reduced. Accordingly, when the predetermined lasting allowance of the back part is wiped-in the required wiping force is reduced to such an extent that there is little danger that the upper material will be marred or otherwise damaged.

Corrugations 24 may also be formed in the lasting margin of the back part around the end during the premolding operation or at any suitable time to aid in the uniform formation of pleats during the subsequent formation of the attaching flange. Fig. 2 illustrates a back part 26 which is substantially the same as the back part of Fig. 1 except that the lower marginal portion is not provided with corrugations. While the presence of corrugations in the lower marginal portion is of advantage in forming the pleats during the subsequent formation of the heel seat flange, such corrugations are not essential and the back part illustrated in Fig. 2 in other respects retains the same advantages as the back part illustrated in Fig. 1.

In the modification illustrated in Fig. 3, the shoulder 30 against which the edge of the last is arranged to engage does not extend inwardly in the plane of the last bottom but extends downwardly therefrom at an angle so that there is only a line contact between the shoulder and the edge of the last which, however, is ample for assisting in positioning the back part on the last in the proper relationship. As in Figs. 1 and 2, the lower marginal portion 32 of the back part extends substantially normal to the last bottom

and to the plane in which the upper edge of the shoulder lies, and accordingly, this lower marginal portion has to be turned less than 90° relative to the shoulder during the formation of the attaching flange and the shoulder itself will be turned during the lasting of the back part through a small angle. In other words, if the narrow shoulder 30 extends at an angle of substantially 45° relative to the bottom of the last this portion will be turned during initial movement of the wipers of a lasting machine substantially 45° relative to the back part, after which the portion 32 will be turned 45° relative to the portion 30 so that two different portions of the lasting margin are each turned 45° in sequence instead of forming one 90° turn as required in lasting the units of Figs. 1 and 2. This arrangement further reduces the force required to wipe-in the lasting margin during the lasting operation and therefore further reduces the possibility of damaging the upper during that operation. As in Figs. 1 and 2, the shoulder 30 is narrow and does not interfere with the conforming of the premolded back part to the last but does provide a gage for positioning the back part in the desired relationship on the last as well as facilitating the subsequent in-wipe of the lasting margin. The lower marginal portion 32 may or may not be provided with corrugations of the type shown in Fig. 1 as desired.

While the back part or quarter assembly has been illustrated as being of the type used in sandal work, it should be understood that the invention is not limited to separate back parts of this type but is applicable to quarter assemblies for all types of shoes.

Having thus described my invention, what I claim as new and desire to secure by Letters Patent of the United States is:

1. As an article of manufacture, a quarter assembly for a shoe, said quarter assembly comprising an upper, lining and counter stiffener of a last on which the shoe is to be assembled and having a lasting margin defined by a circumferential crease, said margin extending substantially normal to the plane of said crease, said crease forming a shoulder about the interior wall of the quarter assembly arranged for engagement with the edge of the last to position the quarter assembly thereon for a subsequent lasting operation.

2. As an article of manufacture, a quarter assembly for a shoe, said quarter assembly comprising an upper, lining and counter stiffener molded substantially to the shape of the heel portion of a last on which the shoe is to be assembled and having a lasting margin defined by a circumferential crease, said margin extending substantially normal to the plane of said crease, said crease forming a shoulder about the interior wall of the quarter assembly arranged for engagement with the edge of the last to position the quarter assembly thereon for a subsequent lasting operation, and corrugations extending heightwise in the lasting margin to facilitate the formation of pleats therein during the lasting operation.

3. As an article of manufacture, a quarter assembly for a shoe, said quarter assembly comprising an upper, lining and counter stiffener molded substantially to the shape of the heel portion of the last on which the shoe is to be assembled, said quarter assembly being formed with a square inwardly projecting shoulder, and a lasting margin extending downwardly from

said shoulder substantially normal to the plane thereof.

4. As an article of manufacture, a quarter assembly for a shoe, said quarter assembly comprising an upper, lining and counter stiffener molded substantially to the shape of the heel portion of a last on which the shoe is to be assembled, said quarter assembly being formed with a downwardly sloping shoulder defining a lasting margin, said margin extending substantially normal to the plane of the upper edge of said shoulder, said upper edge of the shoulder being arranged for engagement with the edge of a last to position the quarter assembly thereon for a subsequent lasting operation.

5. As an article of manufacture, a quarter assembly for a shoe comprising upper, counter and lining pieces adhesively secured together and molded substantially to the shape of the heel portion of a last on which the shoe is to be assembled, said quarter assembly having a lasting margin defined by a circumferential crease molded therein arranged to facilitate the subsequent wiping-in of the lasting margin over the bottom of the last.

6. As an article of manufacture, a quarter assembly for a shoe comprising upper, counter and lining pieces adhesively secured together and molded substantially to the shape of the heel portion of a last on which the shoe is to be assembled, said quarter assembly having a lasting margin defined by a circumferential crease molded therein arranged to facilitate the subse-

quent wiping-in of the lasting margin over the bottom of the last, and heightwise extending corrugations in said lasting margin for facilitating the formation of pleats during said lasting operation.

7. As an article of manufacture, a quarter assembly for a shoe comprising upper, counter and lining pieces adhesively secured together and molded substantially to the shape of the heel portion of a last on which the shoe is to be assembled, said quarter assembly being formed with a square inwardly projecting shoulder defining a lasting margin, said shoulder being arranged for engagement with the edge of the last to position the quarter assembly thereon for a subsequent lasting operation, said margin extending substantially normal to the plane of said shoulder.

8. As an article of manufacture, a quarter assembly for a shoe comprising upper, counter and lining pieces adhesively secured together and molded substantially to the shape of the heel portion of a last on which the shoe is to be assembled, said quarter assembly being formed with an inwardly extending downwardly sloping shoulder defining a lasting margin, the upper edge of said shoulder being arranged for engagement with the edge of the last to position the quarter assembly thereon for a subsequent lasting operation, said margin extending substantially normal to the plane of the upper edge of said shoulder.

LESTER S. MACDONALD.

CERTIFICATE OF CORRECTION.

Patent No. 2,277,770.

March 31, 1942.

LESTER S. MACDONALD.

It is hereby certified that error appears in the printed specification of the above numbered patent requiring correction as follows; Page 2, second column, line 42, claim 1, after "stiffener" insert -- molded substantially to the shape of the heel por- --; page 3, second column, line 30, claim 8, strike out "the plane of", second occurrence; and that the said Letters Patent should be read with this correction therein that the same may conform to the record of the case in the Patent Office.

Signed and sealed this 19th day of May, A. D. 1942.

Henry Van Arsdale,

Acting Commissioner of Patents.
